UNITED STATES PATENT OFFICE

138,169

DESIGN FOR A SANDAL OR SIMILAR ARTICLE

Jack Meltzer, New York, N. Y.

Application February 8, 1944, Serial No. 112,513

Term of patent 14 years

(Cl. D7—5)

To all whom it may concern:

Be it known that I, Jack Meltzer, a citizen of the United States and a resident of New York city, county of Bronx, and State of New York, have invented a new, original, and ornamental Design for a Sandal or Similar Article, of which the following is a specification, reference being had to the accompanying drawing, forming part thereof.

Figure 1 is a plan view of a sandal or similar article showing my new design; and

Figure 2 is a side view thereof.

My design for a sandal as shown is characterized by the manner in which the lacing passes between the sections of the sole so as to give a herringbone appearance, the same being in continuous formation around the entire sole member, thus having the apices pointing toward the toe of the sandal on one side and toward the heel of the sandal on the opposite side.

I claim:

The ornamental design for a sandal or similar article, substantially as shown and described.

JACK MELTZER.
